SWITCH

Donald G. Smellie, Canton, Ohio, assignor to The
Hoover Company, North Canton, Ohio, a cor-
poration of Ohio

Application July 9, 1932, Serial No. 621,553
Renewed October 23, 1933

5 Claims. (Cl. 200—17)

The present invention relates to electric switches and particularly to a multi-circuit-controlling switch. More specifically the invention consists of a simple electric switch comprising a plurality of moving contacts which are selectively operated by a single manually controlled lever for the purpose of controlling the electrical circuits to which the switch is connected.

It is an object of the present invention to provide a new and novel switch adapted to control a plurality of circuits. It is a further object to provide a low voltage electric switch comprising a plurality of moving contacts selectively operated by a single manually controlled lever. It is a still further object to provide an electric switch of novel and simple design which is adapted to control a high and low speed electric motor. These and other more specific objects will appear upon reading the following specification and claims and upon considering in connection therewith the attached drawings to which they relate.

In the drawings in which preferred embodiments of the present invention are disclosed:

25 Figure 1 is a top view of the switch comprising the present invention positioned within a hollow tubular member such as a handle and connected in the high and low speed circuits of an electric motor which is not shown;

30 Figure 2 is a view upon the section line 2—2 of the switch shown in the Figure 1 with the tubular housing partly broken away;

Figure 3 is a section through the switch shown in Figure 2 and upon an enlarged scale, being taken upon the line 3—3 of Figure 4;

Figure 4 is an end view of the switch shown in Figure 3;

Figure 5 is a section upon the line 5—5 of Figure 6 showing a modified embodiment of the present invention;

Figure 6 is a side view of a modified embodiment of the present invention, certain parts being broken away;

Figure 7 is an end view of the modification 45 of the invention shown in Figures 5 and 6;

Figure 8 is a side view, with certain parts broken away, of a still further modification of the present invention;

Figure 9 is a view taken upon the section line 50 9—9 of Figure 8.

Referring to Figures 1 to 4 in particular, a switch constructed in accordance with the teachings of the present invention is shown embodied in a hollow tubular metallic handle 1 of the type found in small tools and apparatus

such as suction cleaners and floor polishers. The switch is indicated generally by the reference character 2 and is shown positioned within the member 1. A current-carrying conduit 3 extends into the handle where its wires are suitably connected, one wire 4 going directly to the switch while the second wire 5 extends through the handle 1 and into electrical connection with the unshown electrical motor from which return the leads 6 and 7, each of which is connected to the switch 2, and which, when electrically connected to the lead 4 pass current through either the high or the low speed winding of the driving motor. In the drawings the leads 4 and 5 are denoted as "Supply" and "Common", the return leads 6 and 7 from the motor being indicated by the terms "Low" and "High". In connection with the general arrangement of the switch within the hollow handle 1 it is to be pointed out that both the 10 conduit 3 and the switch 2 are carried upon a removable cover plate 8 which is suitably secured over the opening 9 in the handle by means such as screws 10, 10.

15 Switch 2 comprises a laminated body 11 which is preferably formed of material such as rectangles of fibre but which is in all events insulating material. As shown, body 11 comprises pieces of fibre suitably secured together by a metallic frame member 12 which extends along 20 the underside of the body and upwardly at one end thereof, being suitably secured thereto as by screws 13, 13.

25 Body 11 is formed with spaced cavities 14a and 14b, the upper edges of which are concave. Within each cavity is a roller contact of metal, indicated by reference characters 15a and 15b, which is adapted to move across the concaved edge and which is spring-pressed thereagainst by means of the fibre plunger or tumbler 16. 30 Each plunger comprises a forked lower end which slidably encloses a pin 17 carried by a partially rotatable pinion or actuator 18 which is itself mounted upon a pin 19 carried by the body 11. A short spiral force-receiving and 35 pending spring 20 encloses a portion of each plunger 16 and, through being in contact at its lower end with the pin 17 carried by the actuator 18, forces the plunger upwardly against the roller 15a or 15b to hold it against its concave 40 guideway and also to force it thereacross with a snap action as actuator 18 is rotated. Frame 12 is provided with openings 21, 21 immediately below each actuator 18 through which a part of the body of that member extends in order 45 50 55

that it may be contacted and rotated, the actuator being provided with radially extending arms 22, 22 which are adapted to contact the sides of openings 21, 21 to limit the extent of 5 the movement.

Stationary electrical contacts are arranged upon the body 11 at the sides of the cavities in such positions that roller contacts 15a and 15b are adapted to seat thereagainst at the ends of 10 their strokes. Adapted to contact the opposite sides of contact 15a when it is in its inner position, that is near the center of the switch, are the stationary contacts 23 and 24; and with the contact 15a seated against these two contacts 15 electric current can flow therebetween. Contact 23 is connected by means of the current-carrying bar 25 to contact 26 which is positioned so as to contact 15b in its outer position while contact 24 is connected through bar 27 to contact 20 28 which is adapted to be contacted by contact 15b in its inner position. The incoming current-carrying lead 4 is shown to be directly connected to contact 26, and so through the bar 25 to contact 23. Independent contacts 29 and 25 30 are positioned so as to receive and contact the flying contact 15b and are spaced so as to be placed in series by that contact with the stationary contacts 28 and 26, respectively. The lead 7 which is connected to the high speed 30 winding of the motor is shown connected to contact 29 while the lead 6, connected to the low speed winding of the motor, is connected to the contact 30.

In order to selectively actuate the moving 35 parts of the switch a new and novel arrangement is provided which comprises a U-shaped controller slide 31 carried immediately below body 11 by means of two U-shaped members 32, 32, the upwardly extending arms of which are carried at the sides of the body by the pivot pins 19, 19 of the actuators 18, 18. Slide 31 is provided between its ends with spaced, upwardly-projecting fingers 33, 33 spaced apart by a distance unequal to that separating pins 19, 19, 45 and which are adapted to extend within the normal radius of the bodies of the actuators 18, 18 which are provided with cut-away sectors 34, 34 for the purpose of receiving the finger members. As is clearly apparent in the drawings the sectors 34, 34 are sufficiently wide to permit the fingers 33, 33 to enter, for the purpose of contacting a side thereof, and also to permit it to leave the sector after having rotated the actuator sufficiently. The relationship is substantially one of pinion and rack, the actuator 18 being the pinion and the slide 31 being the rack having a tooth 33. In order to move the slide a manually operable lever 35 is provided which is pivotally mounted at 36 with- 50 in a downwardly opening slot 37 in body 11, the slot being sufficiently large to permit the necessary angular movement of the actuating lever. A transverse pin 38 connects the lever to the slide 31 at the point at which it extends there- 55 through.

The operation of the switch is extremely simple, there being three possible positions of the actuating lever 35 which can so vary the relationship of the contacts of the switch that 60 the motor to which they are connected will be either disconnected from the line, will have its low speed winding in the line, or will have its high-speed winding in the line. As viewed in Figure 2, the actuating lever 35 is in its extreme 65 left position and the actuators 18, 18 have been

pivoted clockwise resulting in the movement of the flying contacts. Contact 15a is in its outer position in which it is entirely out of the electrical circuit. The contact 15b is in its inner position. In this relationship it is seen that no 5 current passes through the motor as no circuit is completed, only the wire 7 which is connected to one side of the high speed winding of the motor being in series with either of the moving contacts. With the actuating lever positioned as 10 shown in Figure 3, its center or middle position, the electric circuit is completed through the high speed winding of the motor. The pivoting of the lever 35 from the left to the center position has resulted in the moving of slide 31 to 15 the right. The left hand finger 33 has contacted the sector 34 of the actuator 18 of the roller contact 15a and has pivoted that actuator in a counterclockwise direction resulting in the movement of the roller contact from its outer to its 20 inner position where it is held by the spring 20. The right hand finger 33 has just entered the sector 34 of the actuator 18 of the roller 15b and no movement of contact 15b has taken place, it having remained in the position shown in 25 Figure 2. With the switch in this relationship the incoming current passes from lead 4, through the bar 25 to contact 23, across roller contact 15a to contact 24, across bar 27 to contact 28 and thence across roller contact 15b to contact 30 29 which is connected to wire 7 which is connected to the high speed winding of the motor. It is clear that in this relationship the motor will run at high speed.

The third position of the switch is not shown 35 but is believed to be obvious. In the third position the lever 35 will be pivoted to its extreme right position which will be a displacement upon the right of its center position which is equal to that upon the left shown in Figure 2. The pivoting of the lever 35 to the right from the position shown in Figure 3 will result in the further movement of slide 31 to the right. Finger 33 which is in registration with sector 34 of the actuator 18 of contact 15b will pivot that member in a counterclockwise position resulting in the movement of roller contact 15b from its inner position to its outer position in which it will seat against contacts 26 and 30. In this relationship it is clear that current enters 45 through the lead wire 4 into contact 26, across flying contact 15b into contact 30 and from that member to the lead 6, which is connected to the low speed winding of the motor. In this last relationship the motor will clearly rotate at 50 low speed. It is to be noted that roller contact 15a remains in the position shown in Figure 3 but is not a part of the electrical circuit through 55 the motor.

In the modification of the present invention 60 shown in Figures 5 to 7, inclusive, the general arrangement of the switch comprising the invention is substantially the same, certain changes having been made to accommodate a slightly different slide mechanism. According 65 to the present embodiment the slide 31 is not carried by U-members 32, 32 but is instead provided with inwardly extending lugs 40, 40 etc. which slidably seat upon the upper edge of the sides of the frame member 12. The upstanding 70 fingers 33, 33 of the first described embodiment have been replaced by inwardly-extending fingers 41, 41 which are adapted to engage recess sectors 42, 42 which are positioned at the top of the actuators 43, 43 of the present embodiment. 75

Actuators 43, 43 differ from actuators 18, 18 in the first embodiment in that each formed as a U-shaped member having a central portion extending across the width of the body 11, each 5 end of the actuator being pivoted upon a pivot pin 19 and the rotation-limiting arms 44, 44 being positioned upon the opposite side of the switch body from that portion of the actuator containing the sector 42, 42. The actuating lever 10 is again pivotally mounted and extends downwardly through an opening 45 in the slide 31 and, upon being pivoted, slides that member to the right or to the left. The actuation of the moving contacts 15a and 15b is the same as that 15 described in connection with the first embodiment and it is believed that reference to that description will make evident the operation of the present embodiment.

Referring now to Figures 8 and 9, a still further embodiment of the invention is disclosed 20 which, in its broad outline, resembles the embodiment first described. In the present instance, however, the switch 2 comprises a molded body 11 which is made up of two halves rather 25 than a plurality of laminations, the halves of the body being secured together by means of pins 50, 50. The actuators are substantially identical with those described in the first embodiment and are indicated by the same reference 30 character 18, 18. The slide 31 of the present embodiment comprises a slotted plate slidably mounted within an internal guideway 52 which is formed in the body and in place of the upstanding fingers 33, 33 of the first embodiment, or the inwardly extending fingers 41, 41 35 of the second embodiment, the laterally-extending bars 51, 51 are provided which are positioned so as to perform the identical functions performed by the fingers 33, 33 in the first embodiment. In the present instance, the points of 40 attachment of the wires 4 and 6 have been brought to the outside of the body 11 and at the end thereof. In operation this body is identical with that first described.

45 I claim:

1. In an electric switch, a body of insulating material formed with spaced cavities, stationary contacts at spaced points, movable contacts in each of said cavities adapted to contact certain 50 of said stationary contacts, contact actuators in each of said cavities and including spaced portions which alternately project from said cavities in the end positions of said actuators, means mounting said actuators for limited rotary movement, a manually operable controller slidably mounted on said body adjacent said cavities and provided with parts adapted to contact the projecting portions of said actuators, characterized in that upon the movement of 55 said controller with a part in contact with a projecting portion of one of said actuators the movable contact operated by that actuator is moved to a new position and the aforesaid pro-

jecting portion moves out of the path of said controller and a second projecting portion of the same actuator moves into said path and is adapted to be moved therefrom upon the movement of said controller in the reverse direction. 5

2. In an electric switch, a body of insulating material formed with spaced cavities, stationary contacts at spaced points, movable contacts in each of said cavities adapted to contact certain of said stationary contacts, contact actuators 10 in each of said cavities and including spaced projections of insulating material which alternately project from said cavities in the end positions of said actuators, means mounting said actuators for limited rotary movement, a controller for said actuators slidably mounted on said body and adapted to contact said projecting portions of said actuators, a lever pivoted to said body extending past said controller in sliding contact therewith and adapted to move said 20 controller upon said body upon being itself pivoted, characterized in that the movement of said controller while in contact with a projection of said actuator effects the movement of the movable contact connected to that actuator 25 to a new position and the removal of that projection from the path of the controller and the movement of a second projection on the same actuator into that path.

3. In an electric switch provided with a body 30 and with a plurality of snap-action contacts, a plurality of pivoted actuators each connected to a movable contact and adapted to convey an actuating force thereto, a sliding controller on said body including portions extended into the 35 orbits of said actuators, said actuators being constructed and arranged to contact said controller portions to receive pivoting force therefrom, the actuator-contacting portions of said controller being spaced a distance unequal to 40 the distance separating the pivotal centers of said actuators to permit of independent or sequential movement of said actuators.

4. In an electric switch having a body and a plurality of movable contacts, a plurality of 45 actuators pivoted about spaced parallel axes and each connected to a movable contact and adapted to convey an actuating force thereto, stops on said actuators limiting the pivotal movement thereof, a sliding controller on said 50 body including portions extended into the orbits of said actuators, said actuators being recessed to mesh with said portions, the actuator-contacting portions of said controller being spaced a distance unequal to the distance separating 55 the pivotal centers of said actuators to permit of independent or sequential movement of said actuators.

5. The construction recited by the preceding claim in which a handle is pivoted to said body 60 and is connected to said controller in order that said controller may be manually operated.

DONALD G. SMELLIE.
